(57) **CLAIM**

The ornamental design for a convertible frame for moses basket, highchair, or cot, as shown and described.

DESCRIPTION

2. Convertible frame for moses basket, highchair, or cot

2.1 : Front top right perspective of a convertible frame for moses basket, highchair, or cot in an expanded position

2.2 : Right view, the left view being a mirror image thereof

2.3 : Front view with frame expanded, the rear view being a mirror image thereof

2.4 : Top view with frame expanded

2.5 : Bottom view with frame expanded

2.6 : Front left perspective view of a convertible frame for moses basket, highchair, or cot in a contracted position

2.7 : Perspective view of a convertible frame for moses basket, highchair, or cot in an expanded and unfolded position, the opposite perspective view being a mirror image thereof

2.8 : Back top left perspective view of a convertible frame for moses basket, highchair, or cot in an expanded position

The broken lines show portions of the article that form no part of the claimed design. The dash-dot-dash lines define the bounds of the claimed design and form no part thereof.

1 Claim, 8 Drawing Sheets
